Primary Examiner — Darlington Ly*Assistant Examiner* — Daniel J Domino(74) *Attorney, Agent, or Firm* — Fountainhead Law Group P.C.(57) **CLAIM**

We claim the ornamental design for a display screen or portion thereof with graphical user interface, substantially as shown and described.

DESCRIPTION

The FIGURE is a front view of a display screen or portion thereof with graphical user interface showing our new design.

The two outermost broken lines showing a display screen or portion thereof and the other broken lines showing elements of the graphical user interface illustrate portions of the article and do not form part of the claimed design.
